US00D827855S

(12) **United States Design Patent** (10) Patent No.: **US D827,855 S**
(45) Date of Patent: ** Sep. 4, 2018

(54) **ENDOSCOPY TRAINING MODULE**

(71) Applicant: **Coloplast A/S**, Humlebaek (DK)

(72) Inventors: **Anne Bournot**, Paris (FR); **Olivier Traxer**, Paris (FR)

(73) Assignee: **Coloplast A/S**, Humlebaek (DK)

(**) Term: **15 Years**

(21) Appl. No.: **29/546,243**

(22) Filed: **Nov. 20, 2015**

(51) LOC (11) Cl. **24-02**

(52) U.S. Cl.

USPC **D24/224**

(57) **CLAIM**

The ornamental design for an endoscopy training module, as shown and described.

DESCRIPTION

FIG. 1 is a perspective view of an endoscopy training module;

FIG. 2 is a front elevation view of the endoscopy training module illustrated in FIG. 1;

FIG. 3 is a back elevation view of the endoscopy training module illustrated in FIG. 1;

FIG. 4 is a left side elevation view of the endoscopy training module illustrated in FIG. 1;

FIG. 5 is a right side elevation view of the endoscopy training module illustrated in FIG. 1;

FIG. 6 is a top plan view of the endoscopy training module illustrated in FIG. 1; and,

FIG. 7 is a bottom plan view of the endoscopy training module illustrated in FIG. 1.

The broken lines showing lettering, hinge brackets, stacking pegs, and the four bottom surface areas are included for the purpose of illustrating unclaimed portions of the endoscopy training module and form no part of the claimed design.

1 Claim, 7 Drawing Sheets
